United States Patent Office.

BENJAMIN F. MATTOX AND SIDNEY CORSON, OF WEST RIDGE,
ILLINOIS.

Letters Patent No. 88,053, dated March 23, 1869.

IMPROVEMENT IN CHAMFERING-MACHINE.

The Schedule referred to in these Letters Patent and making part of the same.

To all whom it may concern:

Be it known that we, BENJAMIN F. MATTOX and SIDNEY CORSON, of West Ridge, in the county of Macon, and State of Illinois, have invented a new and improved Machine for Chamfering the Chimes of Barrels, Tubs, and the like; and we do hereby declare that the following is a full, clear, and exact description thereof, which will enable those skilled in the art to make and use the same, reference being had to the accompanying drawing, forming part of this specification.

The object of this invention is to provide a simple and effective device whereby the chimes of barrels, tubs, and other similar stave vessels, may be mitred, or "chamfered," so called, in an expeditious and accurate manner; and

It consists in the combination and arrangement of the parts of the device, whereby the same is operated without gearing.

The drawing represents a side view of our invention, also showing, in red color, a sectional view of the chime of a barrel being cut by the knife.

A is the base, or pedestal of the machine, from which rises an upright, B.

The horizontal arm D is provided with a perpendicular part, C, which, with the upright, B, is provided with a series of holes, for the bolts b b, by means of which devices the height of the said arm D is adjusted to suit barrels and other stave vessels of different heights.

The arm D E is not continuous, but jointed, by forming the part E with a tenon-extension, which fits within a corresponding recess in the part D, and is secured in place there by pins, e e, or other devices, which will admit the adjustability of the parts to different lengths.

d is a clamp, serving to support the part E, by crossing underneath the recess and tenon, the ribs of the clamp catching in horizontal slots in the sides of the part D.

The revolving arm, I, bears the chamfering-tool, K,

which is simply a flat cutting-plate of metal, having an eye-lug at each end.

The upper eye-lug is affixed to the arm I by means of a pin, and the lower lug is affixed, by means of a pin, to a perpendicular brace-plate, J, the upper end of which is affixed to the arm, and so arranged as to bring the cutting-tool at the proper angle for chamfering the chime.

The arm is fitted to slide in a head, G, so that the radial distance from the cutter K and its centre of revolution may be adjusted for barrels of different diameters, a pin, n, or other suitable device, being employed to hold the arm in place.

The head G is formed with a round extension, e, serving as a centre, or shaft, on which the arm revolves.

A crank-handle, H, is affixed to the extension e, above the arm E, and serves to revolve the arm, and thus actuate the cutter K.

The brace-plate J contains several holes, so that the cutter may be adjusted to different angles.

The drawing illustrates the manner of operating this machine.

We are aware that chamfering-machines have been operated by gearing, but this forms no part of our invention, and we do not claim it, as the gearing renders a machine heavy and expensive.

We claim as new, and desire to secure by Letters Patent—

The combination and arrangement herein described of the upright, B, adjustable right-angular arm C D, adjustable part E, the crank-head G, revolving adjustable arm I, plate J, and adjustable chamfering-tool K, all operating as described, for the purpose specified.

BENJAMIN F. MATTOX.
SIDNEY CORSON.
